CLAIM

We claim the ornamental design for a removable speaker, as shown and described.

DESCRIPTION

FIG. 1 is front elevation view of the removable speaker.

FIG. 2 is a rear elevation view of the removable speaker of FIG. 1.

FIG. 3 is a left side elevation view of the removable speaker of FIG. 1.

FIG. 4 is a right side elevation view of the removable speaker of FIG. 1.

FIG. 5 is a top plan view of the removable speaker of FIG. 1.

FIG. 6 is a bottom plan view of the removable speaker of FIG. 1.

FIG. 7 is a bottom perspective view of the removable speaker of FIG. 1.

FIG. 8 is another perspective view of the removable speaker of FIG. 1.

FIG. 9 is another perspective view of the removable speaker of FIG. 1; and,

FIG. 10 is another perspective view of the removable speaker of FIG. 1.

The present disclosure provides an ornamental design for a removable speaker.

The broken lines represent the bounds of the claim and form no part thereof. The light semitransparent washed portions as enclosed by the broken lines depict environment and form no part of the claimed design.
